STATIC SHIELDING OF TRANSFORMER WINDINGS

Kentaro Kurita, Hitachi City, Japan, assignor to Hitachi Limited, Tokyo, Japan

Application June 8, 1954, Serial No. 435,310

4 Claims. (Cl. 336—70)

This invention relates to arrangements of static shielding transformer windings, and more particularly to means for shielding transformer windings against steep wave front voltages applied to the windings.

The invention is characterized in that one or more shielding conductors are inserted between adjacent coil turns of the disc coils of a power transformer and said shield conductors provided for different coil layers are electrically connected with each other or with one of the coil conductors.

The principal object of this invention is to provide a positive shield means which can considerably reduce the volume and cost of known electrostatic shielding devices.

It is known that the initial potential distribution in a transformer when a lightning stroke or other peak voltage of steep wave front appears at a terminal of the transformer is determined by the ratio of distributed capacities, i.e., the ratio of the capacitance of coils to earth and the mutual capacitance between coils. This distribution is not linear, but it exhibits a particularly steep potential gradient at the high tension terminal of the winding, which is liable to puncture the insulation of the winding. In order to prevent damage, various contrivances have heretofore been made to level off the steep potential gradient by providing electrostatic shields for the windings. Known shields, however, result in an unavoidable increase in the cost and volume of the transformer.

According to this invention, an effective electrostatic shielding means can be provided for a power transformer without substantially increasing the cost and size of transformer.

For a better understanding of the nature of this invention, reference should be had to the following description in conjunction with the accompanying drawing, wherein:

Fig. 1 is a diagrammatic sectional view of transformer windings illustrating an embodiment of this invention;

Figs. 2 to 5 are diagrammatic views similar to Fig. 1 illustrating modified embodiments of this invention;

Fig. 6 is a diagrammatic representation of an equivalent circuit of a non-shielded transformer, and

Fig. 7 shows an equivalent circuit of transformer windings, to which the shield is applied according to this invention.

Referring now to Fig. 1 of the drawing, the reference numerals 1 to 8 designate conductors in each coil of a power transformer. 9 to 12 represent sheet conductors wound between each pair of turns 1 and 2, 3 and 4, 5 and 6, and 7 and 8 respectively; 13 a high tension terminal, 14 a core. The shield conductors 9 and 10, and 11 and 12 are electrically connected.

Fig. 2 represents a modified embodiment of this invention, in which the shield conductors 9 and 11 in Fig. 1 are dispensed with, while the shield conductors 10 and 12 are electrically connected to a conductor of turns 1 and 5 respectively and all others are the same as in Fig. 1.

Fig. 3 represents another embodiment of this invention.

tion, in which insulated conductors are used in place of shield conductors 9 to 12 in Fig. 1 and also insulated conductors 15, 16, 17 and 18 are wound on the outside of each end turn 1, 3, 5 and 7 in each layer of disc wound coils, and each pair of the conductors 15, 16 and 17, 18 respectively are electrically connected with each other.

Fig. 4 illustrates a further modified embodiment of this invention, in which shield conductors 23, 24, 25 and 26 are wound between each turn 2, 4, 6 and 8 as shown in Fig. 3 and that of the turns 19, 20, 21 and 22 which are located adjacent to the inside of the former turns, respectively. If desired, shield conductors may also be wound between the inner turns.

Fig. 5 illustrates further modified connections of shield conductors wound according to this invention, wherein the shield conductors 15, 9, 23, 23' etc. wound on the outermost and between successive turns respectively of a disc coil layer are connected together with each other and to the coil conductor 3, preferably the outermost turn of the adjacent layer. Similarly the shield conductors 16, 10, 24, 24' etc. of the lower layer are connected together with each other and to the coil conductor 1, and also the shield conductors 17, 11, 25, 25' etc. are connected together with each other and to the coil conductor 7. The shield conductors 18, 12, 26, 26' etc. are connected together with each other and to the coil conductor 5.

Either of bare or insulated shield conductors is selected according to the insulating strength of the insulation covering of conductors, for example, whether the dielectric strength of insulation covering of the conductors 1 and 3 can resist the potential difference between these conductors or not. In disc coils having winding space approximately as shown in these figures, it is sufficient in practice to use a thin copper strip having thickness of about 0.8 mm. or which is provided with relatively thin insulation covering so that the width of each disc coil layer required for receiving the shield conductor is not substantially increased. Though in figures referred to above, several coil layers adjacent to the high tension terminal are shown, it should be noted that a similar arrangement may be provided for lower potential coil layers.

The operation and effect of the electrostatic shield arrangement according to this invention will next be explained. Considering an ordinary transformer which has no shield conductors 9, 10, 11 and 12 as are provided in the embodiment of this invention shown in Fig. 1, the potential distribution in the transformer windings at the moment when a surge voltage of steep wave front has arrived at the high tension terminal 13 may be determined by the condition of distribution of the capacitance to earth and mutual capacitance of the windings. An equivalent circuit is shown in Fig. 6, wherein C_1 represents a capacitance to earth of the innermost turn of a disc coil in each layer, C_2 the capacitance to earth of the outermost turn of a disc coil in each layer, K_1 a capacitance between adjacent turns, and K_2 a capacitance between opposite turns of the upper and lower layers in a set of disc coil layers (usually consisting of two layers arranged in the upper and lower positions as shown in the drawing).

On the other hand, the equivalent circuit for the arrangement shown in Fig. 1, wherein the shield conductors 9 to 12 are provided, will be as shown in Fig. 7. In this figure, K_3 represents a capacitance between a shield conductor, such as 9 and a coil conductor adjacent to the shield conductor, such as 1 or 2.

In ordinary power transformers having no provision of electrostatic shielding for windings, the earth potential V of different parts of windings at the moment when a

high voltage surge has arrived at the high tension terminal of the transformer winding is expressed by the following formula as is well known:

In case of one terminal directly grounded

$$V = E \frac{\sinh \alpha(1-X)}{\sinh \alpha}$$

In case of one terminal open circuited

$$V = E \frac{\cosh \alpha(1-X)}{\cosh \alpha}$$

wherein

E represents a voltage at a terminal of the winding,

X —the measured distance between coil layers assuming the windings to be arranged uniformly from the high tension side towards the lower tension side and taking the total length of the winding as unity,

$$\alpha = \sqrt{\frac{C}{K}}$$

C —capacitance of windings to earth,

K —series capacitance between the high tension terminal and the neutral terminal.

It will be apparent from the above formulae that the potential distribution will become steeper when X is smaller, i.e. at a point nearer to the high tension terminal and that the steepness will be larger when α is greater.

The transformer shown in Fig. 1 which is provided with the shield conductors 9 to 12 wound between turns according to the invention has the following advantages as apparent from the comparison of its equivalent circuit shown in Fig. 7 with that shown in Fig. 6 for the transformer having no electrostatic shield between turns:

(a) The total series capacitance between the coil conductors 1 and 3 in Fig. 6 will be series circuit only in Fig. 7 consisting of K_2 and the upper part K_3 in parallel thereto and the lower part K_3 of series circuit so that the series capacitance between conductors 1 and 3 will be increased.

(b) Coil turns 2 and 4 and all other turns inside of these turns are shielded by the shield conductors 9 and 10 so that the resultant electrostatic capacity is connected in series between the electrostatic capacity between these shield conductors 1 and 3, and the capacitances to earth C_1 and C_1 , and accordingly the capacitance to earth between the turns 1 and 3 and the core 14 will be more reduced than when the capacitance to earth consists of C_1 and C_1 only. Such an effect could never be obtained by any known electrostatic shield device.

In the foregoing description, a twin coil layer consisting of an upper disc coil layer which comprises turns 1, 2 etc., and a lower disc coil layer which comprises turns 3, 4 etc. was taken for the explanation, yet the same applies to the other twin coil layers. Thus the series capacitance K between the high tension terminal 13 and the neutral point is increased and the capacitance to earth C decreases resulting in the reduction of the value of α , thereby making the initial potential distribution coincide with or nearer to the final potential distribution.

In the embodiment shown in Fig. 2, the turns 1 and 9 in Fig. 7 are short-circuited to eliminate the upper K_3 so that the capacitance between coils 1 and 3 is increased.

By providing further shield conductors 15, 16, 17, 18 etc. to the outside of turns 1, 3, 5, 7 etc. as shown in Fig. 3, the series capacity K between terminals can be further increased and the value of α can be reduced further.

The provision of additional shield conductors between coils inside of shield conductors 9, 10 etc. as shown in Fig. 4 is effective to suppress local oscillation.

In Fig. 4, if the coil conductor 2 is connected to the high tension terminal 13, that is, if the coil conductor 1 in Fig. 3 is constituted by split conductors 1 and 2 in Fig. 4 (which are connected together in the manner shown by the broken line in the drawing), the provision of

shield conductors 9, 15, 23 etc. according to this invention enables increasing the electrostatic capacity substantially between conductors 1 and 3. It is found by measurement that the value of α in each of the above embodiments was reduced to about $1/3$ to $1/5$ of that which was obtainable in known devices.

In conventional devices, shield conductors 15, 16 etc. as shown in Fig. 3 were applied to the outside of end turns 1, 2 etc. in each of the coil layers only so that the increase of series capacity per coil layer is relatively small and it is necessary to shield the high tension terminal and successive several coils with the same potential conductors.

In such a case, a voltage difference of a large percent of total voltage appears between coil conductors of lower potential and the shield conductors, and thus the thickness of insulation covering of the shield conductors should be considerably increased in order to resist this magnitude of voltage. The increase in thickness of insulation reduces additional capacitance between coil conductors, and to compensate for this the connection of shield conductors must be extended further to the coil layers of lower potential. This requires a further strengthening of the insulation of the shield conductors, thereby further increasing the size of the shielded coil, which attains a large sectional width. Such bulky shielded windings which project within high tension field from the outer periphery of transformer windings cause an increase in the volume of transformers and also cause troubles in mechanically supporting them. Moreover, this complicates connection between conductors. Thus, an ordinary shielded transformer often costs several times the cost of non-shielded transformers of the same capacity.

As described in the foregoing, the shield conductors according to this invention are sufficient with the use of a thin copper strip of a few millimeters thickness and with an insulation covering of a few millimeters thickness so that the increase in volume of coil layers is substantially negligible. Such a strip may be wound together with the turn in the same winding operation without requiring any other supporting means and it is a surprising advance that the cost necessary for providing a shield device can be reduced to a few percent of that of known devices.

What I claim is:

1. An electrostatic shielding device for a transformer comprising an iron core and a plurality of pairs of disk coil layers each comprising a plurality of turns of insulated conductors wound around said core concentrically thereto, said electrostatic shielding device comprising a plurality of shield conductors wound between at least the two outermost adjacent turns along the winding direction of more than one pair of said disk coil layers, each of said shield conductors in one coil layer being electrically connected with at least one of the conductors in the other coil layer belonging to the same pair.

2. An electrostatic shielding device for a power transformer comprising an iron core and a plurality of pairs of disk coil layers each comprising a plurality of turns of insulated conductors wound around said core concentrically thereto, said electrostatic shielding device comprising a plurality of shield conductors wound together with and between at least the two outermost adjacent turns of more than one pair of said disk coil layers, a shield conductor in one coil layer of a pair being electrically connected with one of said insulated conductors in the other coil layer of the same pair.

3. An electrostatic shielding device for a power transformer comprising an iron core and a plurality of pairs of disk coil layers each comprising a plurality of turns of insulated conductors wound around said core concentrically thereto, said electrostatic shielding device comprising a plurality of shield conductors wound together with and between at least the two outermost adjacent turns of more than one pair of said disk coil layers,

each of said shield conductors in one coil layer of a pair being electrically connected with one of said shield conductors in the other coil layer of the same pair.

4. An electrostatic shielding device for a power transformer having an iron core and a plurality of pairs of disk coil layers consisting of a plurality of turns of insulated conductors wound around said core concentrically thereto, said electrostatic shielding device comprising a plurality of shield conductors, each being wound between the outermost turn and the successive inner turns and outside of the outermost turn in each disk coil layer of a pair, said shield conductors being electrically con-

5
6
nected together with each other and with an insulated conductor in the adjacent coil layer of the same pair.
